Bernard F. Garvey

ATTORNEY.

UNITED STATES PATENT OFFICE.

GEORGE C. EICHENSEHR AND JOHN E. NIESNER, OF JOHNSTOWN, PENNSYLVANIA.

RAIL-FASTENER.

1,383,089.

Specification of Letters Patent. Patented June 28, 1921.

Application filed April 27, 1921. Serial No. 464,861.

To all whom it may concern:

Be it known that we, GEORGE C. EICHENSEHR and JOHN E. NIESNER, citizens of the United States, residing at Johnstown, in the county of Cambria and State of Pennsylvania, have invented certain new and useful Improvements in Rail-Fasteners, of which the following is a specification.

This invention relates to rail fasteners and is especially adapted for use on mine ties.

Objects of the invention are to provide a fastener which will securely hold the rail on the ties; to eliminate the use of spikes or other securing means; to provide a fastener which may be quickly engaged with the tie and rail and likewise quickly and conveniently removed from the tie without disturbing either the tie or rail; and to provide a simply constructed, durable and inexpensive fastener the construction of which reduces possibility of displacing the fastener to a minimum.

Besides the above objects other objects will be apparent from the following description of the present preferred form of the invention taken in connection with the accompanying drawings wherein:

Figure 1 is a fragmentary top plan view of a rail and tie equipped with the invention, one of the fasteners being shown in dotted lines to show to advantage the configuration of the slot in which the fastener is mounted.

Fig. 2 is a longitudinal sectional view through the tie showing the fasteners in side elevation.

Fig. 3 is a vertical sectional view taken on the line 3—3 of Fig. 2 looking in the direction of the arrow, dotted lines being used to indicate the position of the fastener when engaging the same with or disengaging it from the tie, and

Fig. 4 is a fragmentary bottom plan view of a tie constructed in accordance with this invention and equipped with one of the fasteners.

In the drawings a tie 5 is shown which preferably consists of a sheet of metal arched upwardly midway its longitudinal edges and adapted to receive a rail 6 of conventional design. The tie is provided with a pair of T shaped openings or slots 7, one of which is arranged on each side of and in close proximity to the base flange of the rail. The slots extend transversely of the tie and

are preferably arranged approximately midway the opposite margins of the latter. Moreover the slots are by preference arranged in parallelism.

Fasteners made in accordance with this invention consist of bodies or plates 8 each of which has the lower end thereof formed to provide a base or foot 9 which has a neck 10 rising upwardly therefrom, the neck 65 issuing into a head 11. The foot 9 may be relatively smaller than the head 11 as shown in the drawing, although if desired they may both be made of the same size. The foot is adapted to be inserted downwardly 70 through the slot 7 as shown by the dotted lines in Fig. 3, one end of the foot being inclined or beveled to prevent binding of the fastener on the terminal wall of the slot, pursuant to which the neck 10 is urged into 75 engagement with the head 12 of the slot. The fastener is then turned at right angles in which position the bottom of the head 11, at one end, will snugly engage the top of the tie while the bottom of the opposite end 80 is reduced, as indicated at 13, for engagement with the top of the base flange of the rail. By reducing the head as indicated at 13 a shoulder is provided which abuts the free marginal edge of the base flange as 85 shown to advantage in Fig. 2. It will be appreciated that when the fastener is engaged in the head of the slot in this manner that lateral movement of the fastener is prevented due to the fact that the length of 90 the neck is greater than the width of the body of the slot 7. When it is desired to disengage the fastener the head 11 is turned to permit the foot to be raised upwardly 95 through the slot as shown by the dotted lines in Fig. 3.

Various changes may be made in this device especially in the shape of the fastener, proportion and arrangement of parts without departing from the spirit and scope of 100 the invention as covered by the appended claims.

What is claimed is:

1. A rail fastener for ties including a tie having a T shaped slot therein, a fastener for engagement in said slot with a portion thereof arranged above the tie and a portion below the tie, said fastener being engageable in the head of the T slot to prevent lateral displacement of the fastener. 105

2. A rail fastener including a tie to receive a rail and provided with T shaped

slots therein on opposite sides of the rail, a fastener for insertion in each of said slots and engageable with the base flange of the rail, said fasteners being positioned in the heads of said slots, and engaged with the rail, to prevent lateral displacement of the fasteners.

3. A rail fastener including a tie having a T-shaped slot therein, a plate for securement in the head of said slot, the lower end of which is formed to provide a foot for en-

gagement with the bottom face of the tie and equipped with an upstanding neck which extends through the slot and issues into a head, said head adapted to engage the top of the tie and base flange of the rail substantially as described. 15

In testimony whereof we affix our signatures.

GEORGE C. EICHENSEHR.
JOHN E. NIESNER.
